UNITED STATES PATENT OFFICE.

ELMER S. FARRINGTON, OF HARDWICK, VERMONT.

ACCOUNT-PAD.

1,299,316.

Specification of Letters Patent.

Patented Apr. 1, 1919.

Application filed January 16, 1918. Serial No. 212,111.

To all whom it may concern:

Be it known that I, ELMER S. FARRINGTON, a citizen of the United States, residing at Hardwick, in the county of Caledonia and

5 State of Vermont, have invented new and useful Improvements in Account-Pads, of which the following is a specification.

This invention is embodied in an account pad for the use of farmers, the pad being 10 adapted to be used like a bound book in making entries on the different pages, and being also adapted to be filed with other like pads for future reference.

Of the accompanying drawings forming a 15 part of this specification,—

Figure 1 is a perspective view of a pad embodying the invention and a temporary binder therefor.

Fig. 2 is a perspective view of a portion 20 of the pad and the flexible pad cover herein-after described.

Fig. 3 is a perspective view, showing the parts of the temporary binder represented by Fig. 1.

25 Fig. 4 is an edge view, showing the pad and its cover folded for engagement with confining means, such as spindles.

Fig. 5 is a plan view, showing the entire pad unfolded.

30 Fig. 6 is an edge view, showing the pad in the condition represented by Fig. 5.

The same reference characters indicate the same parts in all of the figures.

In the drawings, 12 represents an elongated flexible record strip, preferably of 35 paper, the length of the strip being much greater than its width. The strip is pro-

vided with transverse creases 13 and 13^a adapting it to be folded from the extended

40 condition shown by Fig. 5 to the condition shown by Fig. 4, the strip when folded constituting a series of leaves, arranged book-wise and adapted to be opened and closed like the leaves of a book, some of which are

45 uncut, the edges of the leaves formed by the creases 13^a being equivalent to the uncut edges of two adjacent leaves. One side only of the strip is therefore adapted for use in making entries, and this side constitutes a

50 series of blank pages, and is provided with indicia identifying said pages, as indicated by Figs. 2 and 5.

55 Referring to Fig. 5, it will be seen that one page is identified by the word "Miscellaneous", another by the word "Grain", and another by the word "Groceries," etc. The

indicia for one page may serve also for the adjacent page, as shown by the left-hand end of Figs. 2 and 5, where the word "Miscellaneous" constitutes a heading for the 60 first and second pages.

It will be seen by reference to Fig. 1 that the leaves may be opened and closed without lengthening the pad beyond the combined length of two adjacent leaves, al- 65 though, if desired, the pad may be entirely unfolded and extended, as indicated by Figs. 2, 5 and 6.

One of the end leaves is longer than the other leaves, so that when the pad is folded, 70 as indicated by Fig. 4, an extension or pad head 14 is formed which projects from one end of the folded pad and is adapted to engage confining means, such as the studs 15 on the temporary binder hereinafter de- 75 scribed, or elongated studs or spindles 16, constituting parts of a filing device, one of said spindles being shown by dotted lines in Fig. 4.

In the embodiment of the invention here 80 shown, the pad head 14 is perforated to form orifices 17, adapted to receive either the studs 15, or the spindles 16.

18 represents a flexible cover, one end of 85 which is glued or cemented to the head 14 and reinforces the latter, the orifices 17 being formed also in the cover 18. One leaf of said cover is longer than the other, as shown by Fig. 4, so that when the cover is folded, 90 the head 14 is exposed.

The described pad may be adapted for use during a limited period such as one month, and the head 14 may be provided with exposed indicia identifying the period of use of the pad, as shown by Figs. 1, 2 and 5, 95 showing the word "June" inscribed on the head 14. When the pad is folded and filed away with other pads, it may be readily identified by the exposed indicia above de- 100 scribed.

During the period in which the pad is in use a temporary binder may be employed to protect the pad and serve as a tablet supporting its leaves. As shown by Figs. 1 and 3, said binder is composed of stiff leaves 19 and 20, connected by a flexible hinge portion 21. The above described studs 15 are attached to the leaf 19, said studs being arranged to register with and enter the orifices 17, and adapted to engage suitable holding-down devices adapted to confine the head 14 in contact with the leaf 19. As here shown, 110

the studs 15 are grooved to engage an elastic rubber band 22 which is formed to be stretched by its engagement with the studs.

It is obvious that the elongated strip may 5 have any desired number of creases and leaves. While I have shown seven leaves in the present case, the number in practice will be usually greater.

It will be observed that the inner ends of 10 the leaves formed by the creases 13 are not confined like the inner ends of the pages of a bound book, but are separable from each other, so that the strip may be extended from the folded condition shown by Fig. 4 to the 15 flat, elongated condition shown by Figs. 5 and 6, thus permitting all the pages on which entries are made to be inspected simultaneously, and also permitting quick access to any page, without loss of time in turning the 20 connected pairs of leaves one by one. The front side of the strip is longitudinally ruled to form elongated spaces 12^a extending the entire length of the foldable portion of the strip to receive columns of figures. The head 25 14 is printed to provide headings 12^b, such as the words "Paid," "Received," at the heads of the spaces 12^a, the headings being alined with the spaces. Owing to the fact that the head 14 is exposed and never covered by the 30 body or foldable portion of the strip, the headings 12^b serve to identify the spaces 12^a on each of the leaves, in any adjustment of the pad. When the pad is adjusted as shown by Fig. 1, the headings identify the spaces 35 12^a on the first and second leaves. The pad may be adjusted to bring other leaves into the same relation with the head. For example, the third leaf may be adjusted to cause its end bearing the word "Grain" to adjoin 40 the head 14, so that the headings 12^b will identify the spaces 12^a on the third and fourth leaves, and so on. Memoranda may be entered on the back side of the strip.

I claim:

45 1. An account pad formed by an elongated flexible record strip having transverse creases adapting the strip to be folded into a series of connected leaves arranged book-wise, one side of the strip forming a series

of blank pages, and being provided with 50 headings forming suitable page-identifying indicia, one of the end leaves being elongated to form a head which is exposed when the pad is folded, said head being provided with pad-identifying indicia. 55

2. An account pad formed by an elongated flexible record strip having transverse creases adapting the strip to be folded into a series of connected leaves arranged book-wise, one side of the strip forming a series of 60 blank pages and being provided with headings forming suitable page-identifying indicia, one of the end leaves being elongated to form a head which is exposed when the pad is folded, said head being also provided with pad-identifying indicia and perforated to engage confining studs. 65

3. An account pad comprising an elongated flexible record strip having transverse creases adapting the strip to be folded into 70 a series of connected leaves arranged book-wise, one side of the strip forming a series of blank pages and being provided with headings forming suitable page-identifying indicia, one of the end leaves being elongated 75 to form an exposed head provided with pad-identifying indicia, and a flexible cover cemented to said head to reinforce the latter, one leaf of said cover being longer than the other, whereby, when the cover and pad are 80 folded one side of the head is exposed, the cover and head being perforated to engage confining studs. 85

4. An account pad formed by an elongated flexible record strip having transverse 85 creases adapting the strip to be folded into a series of connected leaves arranged book-wise, one side of the strip being longitudinally ruled to form elongated spaces, one of the end leaves being elongated to form a 90 head which projects from one end of the foldable portion of the strip and is provided with pad-identifying indicia, and with headings alined with said spaces and forming suitable space-identifying indicia. 95

In testimony whereof I have affixed my signature.

ELMER S. FARRINGTON.
